UNITED STATES PATENT OFFICE

1,987,010

CURVILINEAD

Samuel L. Hensley, Kansas City, Mo., assignor of fifty-one per cent to F. E. Gallup and Amber N. Brunson, both of Kansas City, Mo.

Application October 12, 1931, Serial No. 568,228

9 Claims. (Cl. 33—176)

This invention relates to curvilineads, and my object is to produce a device designed more especially for defining approximately true circles of different diameters, symmetrical ellipses of varied size and proportion, and figures of varied size, having substantially equal sized semi-circular or approximately semi-circular ends and approximately flat sides.

A further object is to produce a device of the character mentioned in which the parts when adjusted to form or define a desired line or figure will remain, or may be secured in fixed relation and form a dependable guide for a hand-manipulated pencil, pen or other marking device.

A further object of the invention is to produce a device of the character above-outlined which is of simple, strong, durable and inexpensive construction.

With the general objects named in view, and others as will hereinafter appear, the invention consists in certain novel and useful features of construction and organization of parts as herein-after described and claimed; and in order that it may be fully understood, reference is to be had to the accompanying drawing, in which:—

Figure 1 is a plan view of the preferred form of the device as arranged in full lines for defining a true ellipse, and in dotted lines, a true circle and an elliptical figure having rounded ends and approximately flat or slightly curved sides.

Figure 2 is an enlarged central vertical section taken longitudinally of the handle portion of the device.

Figure 3 is an enlarged fragmentary vertical section of a modified construction.

Figure 4 is a horizontal section on the line V—V of Figure 2.

Figure 5 is a detail perspective view.

Figures 6 and 7 are diagrammatic plans respectively indicating pinched in or distorted and true ellipses, the distortion of the former being due to an insufficient overlap of the free end on the fastened end of the ribbon.

In the said drawing, where like reference characters identify corresponding parts in all of the figures, 1 indicates a thin resilient strip or ribbon of steel or other material, formed at one end with a short laterally-projecting portion or grip 2, and secured flatly at the other end to the rear side of an upstanding plate 3 detachably fastened to the front face of a post 4 having a vertical recess 5 loosely receiving the end of the ribbon fastened to said plate, said post also having an arm 6 projecting to the right for a purpose which

hereinafter appears, the provision of said arm permitting of the use of a post of less width than would otherwise be desirable, it being understood that the ribbon is disposed with one side edge, the bottom edge, facing downward. Said edge is reduced in thickness by having a beveled inner surface 7, and its fastened end at the outer side thereof is tapered to a sharp edge as at 8.

In the preferred embodiment, the post 4 is rigidly secured to and depends from the front end of a horizontally-disposed screw rod 9, which extends slidably through a bifurcated post 10, but has no rotary action, the preferred arrangement to provide for longitudinal movement only being a key-way or slot 11 in the screw rod and a pin 12 secured to the bifurcated post and engaging said keyway or slot, together with a rotatable thumb nut 13 engaging the screw rod and fitting in the bifurcation of said post 10 so that by turning the nut in one direction or the other the screw rod can be advanced or retracted relative to the bifurcated post and thus correspondingly affect the fastened end of the resilient ribbon.

A recessed or slotted post 14 (the slot being as shown in the post 14a of Figure 3), for engaging the resilient ribbon at an intermediate point in its length, especially when it is desired to cause the ribbon to define an elliptical figure or a figure having substantially semi-circular ends and relatively flattened sides, is in fixed relation to post 10 and in alignment with the screw rod. Posts 10 and 14 project upwardly from a base 15 of laterally bowed form to accommodate the largest curvilinear figure the resilient ribbon is capable of describing, and the bottom of the base occupies substantially the same horizontal plane as the lower edge of the ribbon, and may serve as a stabilizer of the ribbon when bent to desired form and therefore under tension, the chief function, however, of the base, being to hold the posts 10 and 14 immovable under the resistance offered by the ribbon to bending movements imparted thereto by the thrust or pull action of the screw rod when advanced or retracted by the rotation of the nut.

The device above described may be used to define circles, symmetrical or true ellipses and what may be termed flattened ellipses, and to arrange it for either type of elliptical figure mentioned, the free end is grasped to bend the ribbon and, at a point near or remote from the "grip" accordingly as the figure to be defined is to be large or small, it is fitted in the recess 5 of the post 4, and thereby caused to lie flatly against the tapered surface 8 of the fastened end (see

Figure 4), the taper permitting the part overlapping it to so lie that a pencil drawn along the lower edge of the ribbon across the joint or juncture point of the overlapping parts, will produce a line 5 without a perceptible jog or break.

To define a circular figure the ribbon at an intermediate point, is engaged with the recess of post 4, but it is not fitted in the post 14, and therefore, through its own resiliency defines a circular 10 figure as indicated in dotted lines 16, Figure 1, and such figure can be made as large as desired within the length of the ribbon or as small as desired by merely adjusting its "grip" toward or from the post 4. The ribbon when not in engagement with 15 post 14, can be reversely bent and held by the hand to define a symmetrical figure semi-circular at one end and tapering to a point at the other, but as this capacity is inherent in any resilient strip, reference is made to it only to indicate that 20 it is not confined entirely for defining circular or elliptical figures. When the device is not required for service, or is to be packed in a box for shipment, the ribbon can be bent to form a relatively small circular figure and fitted in post 14 25 as well as post 4. Its free end can then be fitted also in post 14 far enough back from the "grip" to engage a notch 15a in the inner edge of the base, and the engagement with post 14 and the tendency of the ribbon to spring outward, will 30 insure the retention of the "grip" in said notch (see dotted lines Figure 1).

In the event a true ellipse is to be defined, the nut is turned properly to bring the circularly bent ribbon into position where it can be fitted 35 up into the slot of post 14, or the free end can be slid in post 4 until the circle formed by the ribbon is enlarged sufficiently to permit it to be fitted in said slot, the latter being the quicker adjustment. When thus arranged with the ribbon held 40 at diametrically opposite points, the nut will be turned to feed or slide the screw rod rearwardly. This transforms the circular form of the ribbon into a perfect ellipse (see full lines, Figure 1) with its major axis disposed longitudinally of the device, and as the extent of the rearward adjustment of the screw rod is increased, the elliptical figure correspondingly increases in length and diminishes in width. It was found, especially in 45 forming small ellipses, that where a substantial part of the free end of the ribbon was unconfined and therefore outside of the part actually defining the figure, that such unconfined part had a tendency to project at a tangent from the fastened end too quickly if the post was as narrow as was 50 desired and thus to slightly "pinch" in the rear end of the figure (see Figure 6), and to overcome this without making the post, as a whole, of undesirable width, the arm 6 was formed to extend or increase the length of the bearing on the overlapping part of the strip. The arm transfers the 55 point where the overlapping parts of the strip diverge, to an appreciable distance to one side of the major axis of the ellipse and as a result distortion or pinching of the adjacent end of the figure defined by the ribbon, is avoided, as indicated in Figure 7.

To produce a figure with rounded ends and relatively flat sides, the nut is turned to advance the screw rod and hence apply a push instead of a pull on the ribbon when engaged at an intermediate point with post 14 and nearer the free end with post 4, the major axis of the figure in this instant extending transversely of the screw rod as at 17.

75 It will be noted that the arrangement of the

ribbon in circular or elliptic forms leaves the interior of the figure unobstructed and that the beveled lower edge permits of the use of a ruling pen to reproduce the figure on paper or the like on which the strip rests, with but little chance of smearing because the extreme point of the pen, if reasonable care is exercised, will not contact with the ribbon. 5

In Figure 3 I show a modified construction involving the use of a non-threaded rod 18 adapted for turning movement, which rod carries a slotted post 14a. In this construction no base is employed. This form can be used effectively, but because the rod extends clear across the elliptical figures formed, a pencil or pen cannot be used 10 to inscribe the complete figure in a single sweep, as possible where the base, entirely outside the strip, serves as the support for the front post 14, though it will be understood that if the posts 4 and 14, are tall enough to dispose the screw several 15 inches above the horizontal plane of the strip or ribbon, an elliptical line may be drawn without raising the pen from the paper. As posts 20 as high as suggested would be undesirable, it is contemplated to produce the modified form for 25 use with pencil or stylus markers only.

Referring now in detail to the modified construction, there will be found parts 1 to 7 as in the preferred form. Post 4 however, has a threaded socket 19 having a tapering front end 20 and plate 3 has an opening 21 registering with said socket. Post 4 is formed with a bifurcation in the form shown in Figure 3, said bifurcation or recess 26 receiving the free end of the ribbon when the device is not in use. The recess also serves, when the free end of the ribbon after extending through the recess 5, is bent back to form a figure rounded at one end and tapering to a point at the other, to hold said end adjacent the "grip." 35

In the preferred construction, there is a handle 40 22 mounted on a threaded sleeve 23 whereby the handle is secured in rigid relation to the post 10, and incidentally forms a relatively long guide or support for the threaded rod. In the other construction, there is a handle 24 rigidly 45 secured on a threaded sleeve 25 having a tapered and split front end for engagement with the socket 19, the arrangement being such that by rotating the handle 24 in one direction or the other, its split end is caused by the socket to clamp 50 upon or release the slidable rod for longitudinal adjustment, the adjustment being effected by applying a push or pull on the rod, and when the desired adjustment is secured,—with post 14 of course fitted down on an intermediate part of 55 the ribbon,—the handle is screwed forward to clamp the rod in position and thus retain the ribbon in elliptic form.

From the above description it will be apparent that I have produced a construction which embodies all of the features of advantage set forth as desirable; and while I have described and claimed the preferred embodiment of the invention, I reserve the right to make all changes properly falling within the spirit of the invention and without the ambit of the prior art. 65

I claim:—

1. In a device of the character described, a post, a resilient ribbon secured flatly at one end to the post and so disposed when in use that its lower edge shall engage a surface to be marked; the post having a recess for receiving and holding the free end of the ribbon with its lower edge in the plane of the lower edge of the secured end and with one side fitting flatly against the ex- 75

terior side of its fastened end, the exterior side of the fastened end of the ribbon tapering inwardly to the extremity of such end, and means for engaging the exterior surface of the overlapping part of the ribbon beyond the point where the taper of the end of the ribbon begins, to hold the overlapping portion flatly against and conforming to said taper.

2. In a device of the character described, a post, and a resilient ribbon secured flatly at one end to the post and so disposed when in use, that its lower edge shall engage a surface to be marked; the post having a recess for receiving and holding the free end of the ribbon with its lower edge in the plane of the lower edge of the secured end and with one side fitting flatly against the exterior side of its fastened end, the ribbon being bevelled at the lower edge of its inner side.

3. In a device of the character described, a post, a resilient ribbon secured flatly at one end to the post and so disposed when in use that its lower edge shall engage a surface to be marked; the post having a recess for receiving and holding the free end of the ribbon with its lower edge in the plane of the lower edge of the secured end and with one side fitting flatly against the exterior side of its fastened end, a second post for engaging the ribbon at an intermediate point of its length when the latter is describing a curvilinear figure and fitted at its free end in said recess, and means for applying force to effect relative approaching or receding movement of the posts to force the ribbon to define an elliptic figure.

4. In a device of the character described, a post, a resilient ribbon secured flatly at one end to the post and so disposed when in use that its lower edge shall engage a surface to be marked; the post having a recess for receiving and holding the free end of the ribbon with its lower edge in the plane of the lower edge of the secured end and with one side fitting flatly against the exterior side of its fastened end, a second post for engaging the ribbon at an intermediate point of its length when the latter is describing a curvilinear figure and fitted at its free end in said recess, and a longitudinally adjustable rod secured to one of said posts and movable relative to the other post for effecting relative approaching or receding movement of the posts to force the ribbon to define an elliptic figure.

5. In a device of the character described, a post, a resilient ribbon secured flatly at one end to the post and so disposed when in use that its lower edge shall engage a surface to be marked; the post having a recess for receiving and holding the free end of the ribbon with its lower edge in the plane of the lower edge of the secured end and with one side fitting flatly against the exterior side of its fastened end, a

second post for engaging the ribbon at an intermediate point of its length when the latter is describing a curvilinear figure and fitted at its free end in said recess, a longitudinally adjustable rod secured to one of said posts and movable relative to the other post for effecting relative approaching or receding movement of the posts to force the ribbon to define an elliptic figure, and rotary means to impart longitudinal movement to the rod.

6. In a device of the character described, a base, a pair of posts thereon, a handle secured to one post, a screw rod extending through the handle and the last-named post and in non-rotatable and slidable relation to said post, means for effecting the slidable action of the screw rod, a third post rigidly depending from the front end of the screw rod between the first-named pair of posts, and a resilient ribbon fastened at one extremity to the post rigid with the screw rod and also held by the last-named post in overlapping engagement with the exterior side of said fastened end, and slidably held at an intermediate point by the post beyond the front end of the rod.

7. In a device of the character described, a pair of posts having slots open at one end, a rod slidably engaging one and rigidly carrying the other of said posts, a resilient ribbon for engagement in the slots of said posts and fastened at one extremity to the post bearing a slidable relation to the rod, and a handle fitting on the rod and having a split threaded portion in engagement with the last-named post adapted when screwed firmly into the latter to clamp upon the rod and inhibit movement thereof.

8. In a device of the character described a handle member, a pair of posts carried by the handle member and being relatively movable toward and from each other, and a resilient member for abutment against a member to be marked having one end fixedly and its other end slidably secured to one of said posts, and its intermediate portion being slidably related to said other post.

9. In a device of the character described, a post, a resilient ribbon secured flatly at one end to the post and so disposed when in use that its lower edge shall engage a surface to be marked; the post having a recess for slidably receiving and holding the free end of the ribbon with its lower edge in the plane of the lower edge of the secured end and with one side fitting flatly against one side of its secured end, a second post for engaging the ribbon at an intermediate point in its length, and a rod carrying one of said posts and adjustable longitudinally in relation to the other post to effect approaching and receding movement of said posts.

SAMUEL L. HENSLEY. 60
